UNITED STATES PATENT OFFICE.

EARL KENT AND GLENN KENT, OF TACOMA, WASHINGTON.

DISPENSING DEVICE.

1,422,768.

Specification of Letters Patent.

Patented July 11, 1922.

Application filed May 3, 1921. Serial No. 466,472.

To all whom it may concern:

Be it known that we, EARL KENT and GLENN KENT, both citizens of the United States, and residents of Tacoma, in the 5 county of Pierce and State of Washington, have invented a new and Improved Dispensing Device, of which the following is a full, clear, and exact description.

Our invention relates to a dispensing device, and aims to provide an element of this 10 character more particularly adapted for use in connection with the formation of what is commonly known as an ice cream brick.

It is well appreciated that difficulty has 15 been experienced in making ice cream bricks comprising a plurality of layers of different flavored ice cream. More particularly this difficulty is to be predicated to the time necessary in the making of one of these 20 bricks, and in properly controlling the thickness of the various layers.

Also the mechanism utilized for accomplishing this purpose has been more or less complicated, and consequently expensive, 25 aside from the fact that a further difficulty has also arisen in connection with its utilization.

With this in mind, we have constructed 30 a dispensing device, which may readily be operated, and which will be extremely simple in construction, and readily capable 35 of association with various sizes of freezer cans, and permit of absolute control of the thickness of layers, forming a complete brick being effected.

Still another object of our invention is the 40 construction of a dispensing device of the character stated which may readily be handled, for the purpose of application in all adaptations, and also permitting of its thorough cleansing when this is desired.

Further objects of our invention will appear in the annexed specification, taken in 45 connection with the drawings, which latter present one practical embodiment thereof, and in which;

Figure 1 is a sectional front view taken along the line 1—1 and in the direction of the arrow in Figure 2.

50 Figure 2 is a partly fragmentary side view of the device and showing the same in use.

Figure 3 is a plan view of the same.

55 Figure 4 is a sectional view taken along the line 4—4 of Figure 1, and

Figure 5 is a bottom plan view of the dispensing device.

Referring now more particularly to Figures 1 and 2, it will be seen that the upper end of the dispensing device includes a 60 funnel 5, capable of association with various types of freezer cans 6, by any suitable means such as a hook 7 which may engage the flange of the can 6.

It will also be noted that a pair of handles 65 8 are secured to the outer face of the funnel 5 by any suitable means such as ears 9, and these handles extend at diametrically opposite points from the outer face of the handle and are preferably hollow for a purpose hereinafter more fully specified.

The lower end of the dispensing device includes a nozzle 10, into which the funnel 5 merges, and a suitable controlling element such as a gate valve 11 is associated with the 75 outermost end of the nozzle 10 and serves to control the flow of material from this nozzle, it being noted that the movement of the valve is effected by means of a lever 12 conveniently secured to the nozzle 10 as 80 at 13, and spring pressed as at 14 to normally close the valve.

In use, we preferably apply the funnel end 5 of the dispensing device, to the can 6, subsequent to the removal of the latter's cap. 85 The entire unit thus presented is then inverted and may be supported manually although we preferably utilize a pair of bolts 15 driven into a supporting surface in such a manner as to permit of their extending, 90 one through each of the hollow handles 8.

It will be obvious in any event, irrespective of the method of supporting that an operator will be enabled to effect an actuation of the device by rocking the outer end 95 of the lever 12, which preferably lies in proximity to one of the handles 8, and this rocking will result in an opening of the valve 11 and permit of the material flowing from the nozzle 10 into a suitable mold. It 100 will readily be appreciated in normal operation, that the inner faces of the spout 10 would quickly have the temperature lowered to a point at which the material would cling to the same, and with a view of overcoming this difficulty it will be seen that we may provide a jacket 16 which encircles the outer face of said spout, and, an inlet and discharge pipe 17 and 18 respectively permits of a circulation of a heating medium 110

through this jacket to warm the spout 10 thus obviously permitting of the free flow of material therethrough.

In lieu of this type of heating element we 5 may also utilize, as has been indicated in dotted lines in Figure 1, an electrical resistance element 19, and this will obviously effect the result desired, and in some instances, in a more satisfactory manner than 10 would be provided by the circulation of a heating fluid.

Thus it will be seen that we have provided a dispensing device primarily for use in the 15 adaptation set forth in the preamble of this specification, but not necessarily limited to this particular association, by means of which an extremely simple form of construction is provided permitting of the ready manipulation of the device, as well 20 as positive performance of the functions for which it is intended.

Obviously numerous modifications of structure might readily be resorted to without in the least departing from the spirit of our invention, which we claim as;

25

1. A dispensing device including a funnel, handles secured to said funnel and extending transversely thereto, said handles being hollow and presenting open ends.

2. A dispensing device, including a nozzle, a funnel merging into the upper end of said nozzle, a heating jacket enclosing said nozzle, a gate valve, a lever pivotally secured to said nozzle and having one of its ends attached to said valve, handles secured at diametrically opposite points to the outer face of said funnel, said lever having one of its ends extending to a point in proximity to one of said handles.
